UNITED STATES PATENT OFFICE.

ERNEST CAMP, OF EAST SAN DIEGO, CALIFORNIA.

MEANS FOR COINCIDENTLY PLAYING PIANOS AND ORGANS.

1,232,217.

Specification of Letters Patent.

Patented July 3, 1917.

Application filed September 11, 1916. Serial No. 119,537.

To all whom it may concern:

Be it known that I, ERNEST CAMP, a citizen of the United States, residing at East San Diego, in the county of San Diego and State of California, have invented certain new and useful Improvements in Means for Coincidentally Playing Pianos and Organs, of which the following is a specification, reference being had to the accompanying 10 drawings.

This invention relates to musical instruments and particularly to means whereby one musical instrument, as for instance an organ, may be played from or by the keys 15 of another musical instrument such as a piano.

In theaters, moving picture houses and like places it is oftentimes desirable to play an organ in conjunction with a piano without the necessity of having an extra 20 musician to play the organ.

The general object of my invention is to provide means whereby this may be done at a relatively small expense, this means being so arranged that it may be attached or used with either an ordinary piano or a player piano and with either a player organ or an ordinary organ.

A further object of the invention is the 30 provision of an attachment of this character which uses for its operation the ordinary pneumatics commonly found in player pianos and player organs, thus reducing the cost of the attachment to a minimum.

Other objects will appear in the course of 35 the following description.

My invention is illustrated diagrammatically in the several views in which—

Figure 1 is an end elevation of a piano 40 showing only those parts of the piano which are related to my invention, the view also showing diagrammatically a portion of an organ and the manner in which the valve controlling a single note on the organ is operated and also showing diagrammatically the manner in which the stops are operated;

Fig. 2 is a like view to Fig. 1 but in this case showing the manner in which my invention is applied to a player organ of a 50 common type;

Fig. 3 is a fragmentary front view of a piano partly broken away to show the interior construction and this view also illustrating the stop operating mechanism;

Fig. 4 is an enlarged sectional view of one 55 of the valves whereby the admission of air

to the bellows is controlled, this view showing the valves applied to operating the stop board of an organ;

Fig. 5 is a fragmentary under side view 60 of the vents controlled by the piano keys;

Fig. 6 is a fragmentary perspective view of the front of the piano showing the stop controlling slides;

Fig. 7 is a fragmentary top plan view of 65 two rows or banks of reeds and the controlling boards 21 therefor; and

Fig. 8 is an enlarged fragmentary section of a portion of a piano key, the board 12 and the valve or pad which controls the 70 passage of air through the pipe 13.

Referring now to Fig. 1, 10 designates a piano which may be an ordinary piano or a player piano and 11 designates one of the keys of this piano, it being understood that 75 the mechanism which is used with one key is used with all of the keys. Disposed above the key 11 is a longitudinally extending supporting board 12 from which extends a series of pipes 13, there being as many of 80 these pipes 13 as there are keys and each pipe 13 opens upon the under face of the board, the opening of each pipe in the under face of the board being surrounded by a felt pad 14. Each key 11 carries upon its upper 85 face a felt pad 15 which when the key is raised bears against the under face of the felt pad 14 and prevents air from entering the pipe 13. When the key is depressed air can enter the pipe 13 and pass from there 90 to the primary and secondary valves controlling the bellows which actuate the organ valve.

On the left hand side of Fig. 1 I have 95 illustrated diagrammatically a portion of an organ. In this view 16 designates the wind chest of the organ, 17 the valve which controls the passage of air from the wind chest to the reeds or pipes, 18 and 19 designate two oppositely disposed reed cells or 100 ducts leading to organ pipes, and 20 designates the valve stem. I have illustrated two sets of reed cells 18 and 19 each closed at its outer end by means of a register or stop board 21, hingedly mounted at 22. 105 When one of these stop boards is closed it stops the sounding of all notes of that bank of reeds in the usual and ordinary manner. When either of the stop boards is open of course the corresponding reeds speak. All 110 of these parts are of any well-known or suitable construction and I have not at-

tempted to illustrate the full mechanism of an organ but only sufficient of the mechanism to indicate the manner in which my invention is to be applied thereto.

6 The pipe 13 leads into the organ case and to a valve casing 23 such as illustrated in Fig. 4, this valve case having a partition 24 and a partition 25. The partition 24 is adjacent the bottom of the valve case and is 10 formed with a central opening supporting a diaphragm or pouch 26, while the partition 25 has a central opening 27. The top of the valve case is formed with an opening 28 and with an opening 29 leading into a bellows 30 of the usual form. Disposed within 15 the valve case is a valve stem 31 which at its lower end rests upon the diaphragm 26 and which carries the valves 32 and 33. When the valve 32 is seated in the opening 27, 20 the valve 33 is unseated from the opening 28 and vice versa. Thus when the diaphragm is down, atmospheric air can come through the opening 28 and pass into the bellows. When the diaphragm is raised, 25 however, then communication is established between a pipe 34 and the bellows, this pipe 34 leading to a vacuum chamber 35. It is to be understood that I have shown a very simple form of valve for controlling the bellows 30 but I do not wish to be limited to 30 this as the forms of primary and secondary valves commonly found in player piano and player organ mechanism might be used.

The bellows 30, as illustrated in Fig. 1, 35 has a fixed bottom board 36 and a movable upper board 37 which is provided with a slotted arm 38 which embraces the valve stem 20 and rests upon a stop 39. Normally the bellows 30 is filled with air and is ex- 40 panded and the valve 17 is held against its seat, preventing the passage of air from the wind chest 16 to the reeds or pipes. When, however, the key 11 is depressed it opens the air inlet through pipe 13 and atmos- 45 pheric air passes through the pipe 13 into the space below the diaphragm 26. This raises the diaphragm and allows the valve 32 to establish communication between the vacuum chamber 35 and the bellows, caus- 50 ing the bellows 30 to collapse, depressing the valve 17 and allowing the air to pass to the reeds. Whether the air will pass from the wind chest to one bank of reeds or to both banks of reeds will depend upon 55 whether one or both of the controlling boards or valves 21 are open or closed. It will of course be understood that a small bleed opening 40 is formed in the partition 24 so that when the inlet to the pipe 13 is 60 closed by the release of the key 11, the pressure on opposite sides of the diaphragm 26 will become equalized by the withdrawal of air from beneath the diaphragm 26, this bleed opening, however being so small as not 65 to affect the vacuum between the partitions

24 and 25 when atmospheric air is admitted to the pipe 13.

For the purpose of operating or controlling the stop boards 21 which control the speaking of the different sets of reeds, I 70 have provided practically the same mechanism as for operating the organ valves. This mechanism is illustrated in Fig. 1 and Fig. 4. Extending from the front of the piano in any convenient position, preferably 75 below the keys 11, are a plurality of pipes 41, two pipes being shown, but it being understood that there are to be as many pipes as there are stops or banks of reeds. Each 80 of these pipes 41 leads to a valve casing 23 of the same character as the valve casing 23 heretofore described and having the same arrangement of partitions and valves. This valve casing communicates with a bellows 30^a, the free side of which has a projecting 85 arm 42 which engages with a pin 43 projecting from the corresponding stop board 21. Now it will be obvious that when air is admitted to one of the pipes 41 that this atmospheric air will push up the diaphragm 26 and open communication between the bellows 30^a and the vacuum chamber 35, thus causing the bellows to collapse and this will lift up on the corresponding stop board 21 which will permit that set or bank of 90 reeds to speak. For the purpose of controlling the admission of air to the pipes 41, I provide openings 44 in the face of the piano case and the admission of air to each opening is controlled by a slide 45, as illustrated in Fig. 6, this slide being shown as slotted and mounted upon a guide pin 47. The extremity of each slide is outwardly bent as at 48. The slides may thus be individually manipulated to close or open the 100 stop boards 21 of any particular bank of reeds but for the purpose of simultaneously operating all of the slides, I provide a shiftable rod 49 having a handle 50 and formed with upwardly extending pins 51 which extend up on each side of the finger piece 48, these pins, however, being spaced sufficiently far apart as to permit the shifting of the slide independently of the rod 49. When, however, the rod 49 is shifted all of the 105 slides are opened or closed. The openings 44 may be made and preferably are made in a separate board which I will hereafter term a stop control board, thus avoiding marring the piano, there being flexible tubes leading 110 from the openings 44 of the stop control board to the several valve casings 23 which control the operation of the bellows 30^a. It will of course be understood that while I have only shown two pipes 41 and two sets 115 of banks of reeds, yet this is purely for illustrative purposes and that the same controlling means can be used for any number of stops, banks or sets of notes.

In Fig. 2 I have shown the construction 120

as applied to the control of a player organ. The piano mechanism is precisely the same as heretofore described and hence the same reference numerals are used for it but in this case the pipes 13 extend into the organ case and are connected by means of T's 52 to the pipes 53 which terminate adjacent the keys 54, these keys carrying the usual valves 55 which when the key is depressed move away from the opening of the pipe 53 so as to permit atmospheric air to pass up through the pipe 53 to the usual valve mechanism contained in the valve case 56. This valve mechanism controls the bellows 57, each bellows being operatively connected to the valve pin 58 which permits the passage of wind from the wind chest to the separate reeds. The sounding or speaking of the several banks or sets of reeds is controlled in the same manner as heretofore described by the stop boards 59, these stop boards being controlled by a bellows 60, in turn connected to the valve mechanism illustrated in Fig. 4 and actuated by means of air passing through the controlling pipes 61, these pipes 61 leading back into the piano and opening upon the controlling board, as heretofore described, and being controlled by the mechanism illustrated in Fig. 6 and heretofore described. In Fig. 2 I have merely illustrated in a general way the ordinary mechanism of a player organ and have not attempted to show the details of construction for the reason that these details form no part of my invention and are well known to all those skilled in the art. It is reiterated that the illustration in Fig. 1 and Fig. 2 is largely diagrammatic and while I have illustrated the pipes as leading downward beneath the piano and beneath the floor and up into the organ, it is of course to be understood that these pipes may lead directly from the back of the piano through the back of the organ. The pipes which connect the piano to the organ will be preferably of flexible material such as rubber and hence will permit the piano and organ to be disposed in any suitable positions with relation to each other.

It will be seen that by the use of the mechanism which I have described it is possible to play a number of key actuated instruments simultaneously and that it is not necessary for any one buying the mechanism which I have described to use any special kind of piano or special kind of organ. The piano is connected up with whatever form of organ may be in the theater or auditorium, whether this organ be a common reed organ or an expensive pipe organ, and the organ is played from the piano key board. There are today a great many player organs which have lost their popularity with the public but which may be put to use by installing them in small

theaters and like auditoriums and playing them from the usual piano key board, thus securing effects not otherwise possible at a very cheap cost.

What I claim is:

1. Mechanism for coincidentally playing a wind instrument having a controlling valve and a piano, including a pneumatic operatively connected to a controlling valve of the wind instrument, an air pipe having an air entrance opening, a piano key, and a pad carried by the piano key normally closing said opening of the air pipe but permitting the admission of air thereto upon a depression of the key. 70

2. The combination with a piano and an organ, the piano having keys and the organ having the sound controlling valves, of air pipes, one for each valve and key, each having an air entrance opening disposed in proximity to a corresponding piano key, and a pad carried by each piano key and normally closing the opening of the corresponding pipe but permitting the inlet of air thereto upon a depression of the key whereby to coincidentally operate a pneumatic controlling the corresponding valve of the organ. 80

3. Mechanism for controlling the operation of organ banks from pianos including a controlling device normally preventing the speaking of a plurality of wind operated sound creating devices, means for shifting the controlling device comprising a pneumatic operatively connected to the controlling device, means on the piano for operating the pneumatic comprising a pipe leading from the pneumatic to the piano, and a manually operable member controlling the admission of air to the pipe. 95

4. Mechanism for controlling the operation of organ banks from pianos including a plurality of controlling devices normally preventing the speaking of a plurality of sets of wind operated sound creating devices, means for shifting the controlling devices comprising pneumatics each operatively connected to a controlling device, means on the piano for operating the pneumatics comprising a plurality of pipes leading from the pneumatics to the piano, manually operable slides each controlling admission to one of said pipes, each slide being operable independently of any other slide, and means for simultaneously operating all of said slides. 105

5. Mechanism for controlling the operation of organ banks from pianos including a plurality of controlling devices normally preventing the speaking of a plurality of sets of wind operated sound creating devices, means for shifting the controlling devices comprising pneumatics each operatively connected to a controlling device, a plurality of pipes leading from the pneu- 125

matics to the piano, a plurality of manually operable slides each controlling admission to one of said pipes, each slide having an outwardly projecting thumb piece, 5 and means for simultaneously operating all of said slides including a slidable rod having pairs of pins, each pair of pins being disposed on opposite sides of the thumb piece of one slide, the space between each 10 pair of pins being sufficient to permit the individual operation of the slide.

6. The combination with a piano including a series of keys and an organ including a series of valves, of means for operating 15 said valves from the piano keys comprising a series of pneumatics operatively connected

to the valves, a supporting member extending across and above the piano keys and having a series of perforations, one for each key, pipes connecting said series of perforations each with one of said pneumatics, and pads carried upon the piano keys and normally closing said perforations but movable from the perforations to permit the entrance of air upon the depression of the 25 keys.

In testimony whereof I hereunto affix my signature in the presence of two witnesses.

ERNEST CAMP.
